CLAIM

The ornamental design for a vehicle bumper, as shown and described.

DESCRIPTION

FIG. 1 is a top isometric view of a vehicle bumper, showing an embodiment of our new design.

FIG. 2 is a front elevational view thereof.

FIG. 3 is a rear elevational view thereof.

FIG. 4 is a right side elevational view thereof.

FIG. 5 is a top plan view thereof.

FIG. 6 is a bottom plan view thereof.

FIG. 7 is a top isometric view of a vehicle bumper, showing another embodiment of our new design, which is a mirror image of the vehicle bumper shown in FIGS. 1-6.

FIG. 8 is a front elevational view thereof.

FIG. 9 is a rear elevational view thereof.

FIG. 10 is a left side elevational view thereof.

FIG. 11 is a top plan view thereof; and,

FIG. 12 is a bottom plan view thereof.

Stippling and tangency lines in the drawings represent the three-dimensional contours of the design, and are not intended to indicate surface decoration. The broken lines shown in the drawings depict portions of the vehicle bumper that form no part of the claimed design.
